UNITED STATES PATENT OFFICE.

YASUDIRO SAKAI, OF EAST PITTSBURGH, PENNSYLVANIA, ASSIGNOR TO WESTINGHOUSE ELECTRIC AND MANUFACTURING COMPANY, A CORPORATION OF PENNSYLVANIA.

VAPOR ELECTRIC APPARATUS.

1,148,628.

Specification of Letters Patent. Patented Aug. 3, 1915.

Application filed June 14, 1912. Serial No. 703,663.

To all whom it may concern:

Be it known that I, YASUDIRO SAKAI, a subject of the Emperor of Japan, and a resident of East Pittsburgh, in the county of Allegheny and State of Pennsylvania, have invented a new and useful Improvement in Vapor Electric Apparatus, of which the following is a specification.

My invention relates to vapor-electric apparatus, and particularly to current rectifiers that are employed for changing high voltage alternating current into direct current.

The object of my invention is to provide a vapor electric device having walls surrounding the anodes of such construction as to provide for effective ventilation and cooling of the anodes.

In the single figure of the accompanying drawing, which is a view in side elevation and in section of a rectifier embodying my invention, the rectifier is shown as comprising a substantially pear-shaped casing 1 containing a pool of mercury 2 in its lower smaller end which constitutes a vaporizable cathode. Extending at slight inclinations into the upper larger end of the pear shaped casing are two anodes, each of which comprises a leading in-wire 3 and the anode proper, which is here shown in the form of a cup 4, but which may have any other suitable shape. The anode 4 is located in, and is surrounded by, a tubular envelop or casing 5, the lower end of which opens into the main casing 1 and is preferably bent or shaped to open toward the wall thereof, the upper end of the said tube being sealed around the leading in-wire. The tubular envelop 5 is supported by an outer envelop 6 that is sealed or united at its upper end to the casing 1, and at its lower end to the envelop 5 at a suitable distance below the anode 4, the said outer envelop being enlarged or expanded adjacent to the upper end of the inner envelop 5 in order to provide a ventilating space of suitable width. Extending into the upper end of the envelop 6 is a tube 7 that is supported by means of a suitable number of arms 8, and the lower end of which is enlarged and surrounds the upper closed end of the envelop 5.

During the operation of the device, it is immersed in any suitable cooling medium

such as oil, and, consequently, the spaces between the inner and outer envelops 5 and 6 are filled with oil. As the outer envelop 6 provides a ventilating space surrounding the inner envelop adjacent to the anode 4, the heat given off at the anode during the operation of the device is conveyed away by the oil which is caused to circulate, the circulation of the oil being promoted by the tube 7, which serves, in effect, as a chimney, and causes the heated oil to rise more quickly than it otherwise would.

I claim as my invention:

1. A vapor-electric or similar device comprising a casing, a terminal member extending into the casing, an envelop for the terminal member opening into the casing, and a second envelop surrounding the aforesaid envelop adjacent to the terminal member and opening to the exterior of the casing.

2. In a vapor-electric or similar device, the combination with a terminal member and an envelop therefor, of another envelop surrounding the aforesaid envelop adjacent to the terminal member, and a tube extending into the outer envelop and adjacent to the end of the inner envelop.

3. A vapor electric device comprising a casing, a terminal member extending into the casing, an envelop for the terminal member opening into the casing, and a second envelop united at its ends respectively to the casing and to the aforesaid envelop and providing a ventilating space adjacent to the terminal member.

4. A vapor electric device comprising a casing, a terminal member extending into the casing, an envelop for the terminal member opening into the casing, a second envelop united at its ends respectively to the casing and to the aforesaid envelop and providing a ventilating space adjacent to the terminal member, and a tube extending into the outer envelop and adjacent to the end of the inner envelop.

In testimony whereof, I have hereunto subscribed my name this 31st day of May, 1912.

YASUDIRO SAKAI.
